[21] Appl. No.: 544,487

CLAIM

[22] Filed: Oct. 24, 1983

The ornamental design of a wagon playground climber and slide, substantially as shown and described.

[52] U.S. Cl. D21/244

DESCRIPTION

[58] Field of Search D21/242-245,
D21/250; 272/113

FIG. 1 is an elevational view of my wagon playground climber and slide as taken from the right side thereof, the left side being the mirror image thereof;
FIG. 2 is a top plan view;
FIG. 3 is a front elevational view of my new design, and
FIG. 4 is a rear elevational view.
